UNITED STATES PATENT OFFICE.

HENRY B. KEIPER, OF LANCASTER, PENNSYLVANIA.

CENTRIFUGAL SEPARATOR.

SPECIFICATION forming part of Letters Patent No. 736,978, dated August 25, 1903.

Application filed September 11, 1901. Serial No. 75,091. (No model.)

To all whom it may concern:

Be it known that I, HENRY B. KEIPER, a citizen of the United States, residing at Lancaster, in the county of Lancaster and State of Pennsylvania, have invented certain new and useful Improvements in Centrifugal Separators; and I do hereby declare the following to be a full, clear, and exact description of the invention, such as will enable others skilled in the art to which it appertains to make and use the same.

This invention relates to centrifugal separators; and it consists, substantially, in the improvements hereinafter more particularly described, and pointed out in the claims.

The principal object of the invention is to provide means for subjecting fresh or whole milk to successive skimmings at one continuous operation and discharging the resultant cream of all the skimmings simultaneously with the discharge of the blue or skimmed milk.

A further object is to provide a machine of this character which is much more reliable and effective in use than many others hitherto employed and also to simplify the construction of the machine, as well as to reduce the cost of manufacture and working thereof.

These and additional objects I attain by the means substantially as illustrated in the accompanying drawings, in which—

Figure 1 is a vertical sectional elevation of a centrifugal separating-machine constructed and arranged in accordance with my invention, and Fig. 2 is a top or plan view of the bowl with the cover or cap-piece removed. Fig. 3 is a side elevation of the internal structure of the machine or apparatus which forms the different skimming or separating compartments or chambers. Fig. 4 is a similar view, in part section, showing a slight modification. Fig. 5 is a sectional detail plan view to more clearly indicate the construction of certain parts.

In carrying my invention into effect I employ a suitable rotatable bowl that is provided with an internal structure comprising a number of division-plates or partitions dividing the interior of said bowl into different skimming chambers or compartments, the latter being in communication through suitable passages in said plates or partitions and suit-

able means being provided for the upward travel and discharge of the cream resulting from the different skimmings. A central feed-tube is employed having outlets at or near its lower end for the escape of the fresh or whole milk into the first or lowermost skimming or separating chamber, and suitable means are provided in the cover or cap-piece of the bowl for the final outlet or discharge of both the cream and skimmed milk into suitable receptacles which may be provided therefor. The machine is simple in construction, effective in operation, and is capable of different embodiments, as will hereinafter appear.

Specific reference being had to the accompanying drawings, A represents an outer stationary casing, in which is located the rotatable bowl B, mounted upon suitable ball-bearings *a b* in the bottom of the casing and having a central stem or shaft *c* at the bottom, to which suitable means (not shown) may be connected for operating said bowl. The wall of the bowl is recessed at the upper edge and threaded at *d* to receive a corresponding inner thread formed on the cover or cap-piece C, the said cover or cap-piece screwing tightly thereon, so as to prevent escape of the liquid. The said cover or cap-piece C is formed at different points with escape-passages *f* for the blue or skimmed milk, and the same is also formed with an enlarged central opening *g*, into which is fitted the end of a suitable supply-pipe (not shown) leading from any suitable source of supply of fresh or whole milk. A central feed-tube D is located in the bowl B, and in the wall of the central opening *g* at any suitable point is a vertical cream-passage *h*, that is controlled by means of a screw-plug or valve *i*, working in an opening in the side of the cover or cap-piece C and abutting the side of said central tube D when closed. The said central feed-tube D at its upper end projects into and snugly fits the said opening *g*, while the lower end thereof rests upon the bottom of the bowl and is preferably enlarged at *k*, so as to form an annular projection or flange *l*, for the purpose hereinafter described. Escape-passages *k'* are formed in the side of said tube at or near its lower end. Surrounding the said central feed-tube at suitable distances apart are the division-plates or parti-

tions E, which separate or divide the interior of the bowl B into a number of skimming or separating chambers 1, 2, 3, 4, and 5, respectively, the bottom or lowermost chamber 1 being preferably somewhat greater in height than the others. Any number of said division-plates or partitions can be employed, and consequently any number of skimming or separating chambers, and each plate or partition is formed or provided with curved or other shaped passages m, through which the milk passes from one chamber to the other in the operation of successively skimming or separating the cream. Any number of said 15 passages m may be employed, and they are preferably arranged as near the axes of the division-plates or partitions as possible in order to secure the best results. Each plate or partition E is formed with a central opening n, larger in diameter than the outer diameter of the central feed-tube D, and said plates are held in position upon or about the tube by means of ribs or projections o in such manner as to form coinciding ducts or channels 20 25 o' for the passage of the cream in its ascent or climbing around the outer sides of the said feed-tube. Said ribs or projections o may extend practically the full length of the feed-tube, (see Figs. 1 and 3,) beginning at near the upper end and ending at the flange l, upon which latter they rest, or they may comprise simple lugs p, (see Fig. 4,) each of a height about equaling the thickness of the said division plates or disks. However they may 30 35 be formed a suitable ring or collar q is preferably provided around the feed-tube at the upper end, both as an abutment for the inner flange r of the cover or cap-piece and to insure the complete closing of said opening 40 45 around the tube. Preferably I construct the said ribs or projections o as in Figs. 1 and 3 and unite the collar q therewith in skeleton form, and then slip the structure down over the central feed-tube D. It is immaterial, 50 55 however, whether this construction be resorted to or whether said ribs or projections and said collar are formed on the sides of the tube itself. The division-plates or partitions E are secured at the proper heights in any suitable manner, and they are preferably so disposed that the passages m thereof are brought directly in line or coincident with each other vertically, although this is not essential. Said division-plates or partitions 60 65 are of a diameter equaling the internal diameter of the bowl, and located directly beneath each of the said plates is an annular disk t of a diameter somewhat less than the plates and preferably, though not essentially, inclined on its upper surface and hollow or concaved on its under surface. Said disks are preferably formed rigidly with the division-plates or partitions; but it is immaterial in what manner they are supported in 70 75 position. They are each likewise formed with a central opening u by which to surround the feed-tube and permit of the ascent

or climbing of the cream in like manner, as already described with reference to said division-plates or partitions.

The apparatus being constructed and arranged substantially as herein shown and described, the operation is as follows: The fresh or whole milk flows into the central feed-tube D and passes down the same and escapes 75 into the lowermost separating or skimming chamber 1 through escape-passages h', where it is immediately subjected to the action of the centrifugal force generated by a rapid rotation of the bowl. The skimmed or blue milk is thrown outwardly against the inner side of the wall of the bowl, while the cream flows inwardly toward the center of the apparatus. The skimmed milk being thus obstructed is compelled to move upwardly, 80 85 though still having an outward tendency, and as it reaches or comes into contact with the under side of the first or lowermost division-plate or partition E it is again obstructed and is compelled to again seek the center 90 of the machine, (passing between lowermost plate or partition E and the lowermost disk t,) where it escapes upwardly through the passages m in said plate and passes from the first skimming or separating chamber into the second. The same action occurs in the next chamber, and so on. As the skimmed or blue milk is thus continuously ascending the action of the disks t is to spread the same outwardly, and thus prevent any admixture thereof with the cream, which meanwhile is climbing or ascending the sides of the feed-tube D. On reaching the uppermost skimming or separating chamber 5 the skimmed or blue milk escapes through the openings or passages f in the 95 100 cover or cap-piece C, while simultaneously with such escape the cream escapes through the passage h. The discharge of the cream can be regulated in an obvious manner by the valve i, and it is evident that the ascent 105 of the cream around the sides of the feed-tube D takes place simultaneously with the gradual upward passage of the milk from one skimming or separating chamber to the other. It is apparent that I am not limited to the 110 precise details of construction herein shown and described.

Having thus fully described my invention, what I claim as new, and desire to secure by Letters Patent of the United States, is—

1. In a centrifugal separator, a rotatable bowl having a central feed-tube therein and transversely divided interiorly into a number of independent separating-chambers, which open around and a sufficient distance from the feed-tube to provide a central cream-passage, and milk-passages between the adjacent chambers located intermediate said feed-tube and the periphery of the bowl, substantially as described.

2. In a centrifugal separator, a rotatable bowl having a central feed-tube therein, and a surrounding series of transverse partitions of a diameter equaling the interior diameter

of the bowl, said partitions having central openings sufficiently larger than the tube to leave a central cream-passage and having intermediate milk-passages therein, substantially as described.

- 5 3. In a centrifugal separator, a rotatable bowl having a central feed-tube therein, and a surrounding series of transverse partitions of a diameter equaling the interior diameter 10 of the bowl, said partitions having central openings sufficiently larger than the tube to leave a central cream-passage and having intermediate milk-passages therein, with a series of disks interposed between said partitions and having similar central openings and diameters less than the interior diameter of the bowl, said disks being adapted to deflect the milk toward the periphery of the bowl, substantially as described.
- 15 4. In a centrifugal separator, a rotatable bowl having a central feed-tube therein and transversely divided interiorly into a number of independent separating-chambers, which open around and a sufficient distance from 20 the tube to provide a central cream-passage, milk-passages between adjacent chambers located intermediate said tube and the periphery of the bowl, and means for deflecting the milk in each chamber toward the periphery 25 of the bowl before it passes to the next chamber, substantially as described.

- 30 5. In a centrifugal separator, a rotatable bowl having a central feed-tube therein, a surrounding series of transverse partitions of a 35 diameter equaling the interior diameter of the bowl, said partitions having central openings sufficiently larger than the tube to leave a central cream-passage and having intermediate or surrounding milk-passages, and inclined annular disks of less diameter and having similar central openings, each located beneath a partition with its inner periphery or apex adjacent thereto and inclosed within the milk passage or passages thereof, substantially 40 as described.

- 45 6. In a centrifugal separator, a rotatable bowl having a central feed-tube therein, a series of transverse partitions spanning the liquid-space of the bowl and of a diameter 50 equaling the interior diameter thereof, said partitions having intermediate milk-passages

therein and a series of disks of less diameter, each located adjacent to one of said partitions, said partitions and disks having registering openings around the feed-tube, substantially as described.

55 7. A centrifugal creamer, comprising a rotatable bowl, a central feed-tube therein, a series of division-plates surrounding said tube of a diameter equaling the interior diameter of the bowl and each having a milk-passage therein and a central opening larger in diameter than said tube, a disk located beneath each division-plate and having a similar central opening, and means for sustaining said plates and disks in proper position within the liquid-space of the bowl, substantially as described.

60 8. A centrifugal creamer comprising a rotatable bowl, a central feed-tube therein having passages at or near its lower end for the escape into the bowl of fresh or whole milk, division-plates surrounding said tube and of equal diameter with the interior of the bowl, each plate having milk-passages therein, and having a central opening larger in diameter than said tube, a disk located directly beneath each division-plate, and having a similar central opening about the tube, and projections between said tube and the openings in said division-plates, substantially as described.

65 9. A centrifugal creamer comprising a rotatable bowl, a central feed-tube therein for fresh or whole milk, a series of plates surrounding said tube; the diameters of said 70 plates being equal to the internal diameter of the bowl, so as to divide the bowl into separate and independent skimming-chambers, said plates each having a central opening of greater diameter than the external diameter 75 of the tube, and a disk located beneath each of said plates having a similar opening therein, and means between the tube and the walls of the openings in the plate for maintaining the latter in position, substantially as shown 80 and described.

85 In testimony whereof I affix my signature in presence of two witnesses.
